PARALLEL RULER

Julius Lachmund, San Francisco, Calif.

Application December 4, 1944, Serial No. 566,412

5 Claims. (Cl. 33—110)

1

My invention relates to a drafting triangle having a slide operable to regulate movement of the triangle for section lining to obtain uniform spacing of the section lines.

It is among the objects of my invention to provide a triangle having a slide mounted for reciprocating movement upon the triangle and operable to facilitate use of the triangle for section lining without interfering with its usefulness and operation for other purposes.

Another object of my invention is to provide a structure adapted to facilitate the assembly of the device and its operation for obtaining uniform spacing of section lines.

Another object is to provide a structure of a thickness not materially greater at any point than the thickness of the triangle; and which may be readily adjusted to obtain a desired spacing of section lines drawn at any angle.

My invention possesses other objects and features of value, some of which with the foregoing will be set forth in the following description of the invention. It is to be understood that I do not limit myself to the showing made by the said description and the drawings as I may adopt variant forms of the invention within the scope of the appended claims.

Referring to the drawings:

Figure 1 is a fragmental view, drawn upon an enlarged scale, illustrating the structure and mounting of the slide, parts being shown in section, and

Figure 2 is a plan view of the drafting instrument.

In terms of broad inclusion, the drafting instrument of my invention comprises a triangle provided with a slide mounted for limited reciprocating movement within a guide slot adjacent one of its edges, and operable for regulating movement of the triangle to obtain uniform spacing of lines drawn along its edge. The invention contemplates a structure in which the thickness of the slide is substantially the same as that of the triangle; and in which end pieces, assembled upon the triangle through a widened portion of a guide slot, are adjusted by means of a turnbuckle to vary the length of the slide and the range of movement thereof relative to the triangle.

In terms of greater detail, the drafting instrument of my invention comprises a triangle, designated in general by the numeral 1, which may be of any suitable size and material. The 45° form of triangle shown in the drawing is illustrative only, as a 30°-60°, or other form is equally useful.

A guide slot 2 is formed in the body of the triangle parallel to one of the edges of the triangle and spaced slightly inwardly therefrom. Tongues 3 along the longitudinal edges of the slot provide guide rails for engaging corresponding grooves 4 in the edges of a slide mounted for reciprocating movement within the slot 2.

The slide comprises a pair of substantially rectangular end pieces 7 slidably movable along the guide rails 3 of the slot 2. The pieces 7 are made of material of substantially the same thickness as the body of the triangle 1; and are assembled into the slot 2 through a widened section 8 formed substantially midway between the ends of the slot. The widened section 8 is of a length slightly greater than the length of the end pieces 7. The length of the slot 2 is sufficient to permit at least one of the end pieces 7 to be moved clear of the widened portion 8 of the slot so as to admit the other end piece.

The end pieces 7 are adjustably connected to each other by means of a turnbuckle comprising a sleeve 11 engaging oppositely threaded stems 12 secured to the end pieces 7 in inwardly extending axial alignment. The stems may be screwed into the end pieces after they are assembled onto the triangle, or the parts may be assembled and secured in place in any convenient manner. The sleeve 11 is of a diameter substantially equal to the thickness of the triangle. Preferably the surface of the sleeve is knurled or otherwise roughened to facilitate turning the sleeve to adjust the spacing of the end pieces. Also, such knurling provides a roughened area which aids in holding the slide against a drawing when in use.

The end pieces 7 may be spread apart to seat against the ends of the slot 2 in an inoperative position. When in this position, the slide in no way affects or interferes with the normal operation of the triangle in its ordinary usage.

When it is desired to use the triangle for section lining, the turnbuckle is operated to draw the end pieces 7 toward each other until a desired range of movement of the slide along the slot 2 is permitted. A scale 14 may be provided at one end of the slot 2 for indicating the distance through which the slide may be moved, the scale being readable with respect to one end of the slide as a pointer when the other end of the slide is seated against the adjacent end of the slot 2.

After the end pieces of the slide have been adjusted to give the desired degree of movement, the triangle is placed against a straight edge (not shown) with the slide parallel thereto. The

55

slide is moved to the extreme right hand limit of its movement and the triangle is placed at the starting position for the section lining. An initial section line is drawn, and while the slide is held firmly in place against the drawing, the triangle is shifted along the slide to the next position as indicated in dotted lines in Figure 2. The knurling of the sleeve 11 aids in preventing shifting of the slide as the triangle is so moved. The triangle is then held against the drawing while the slide is moved to the opposite end of the slot, for defining the next limit of movement of the triangle. By alternately moving the slide and the triangle while holding the other against the drawing, the triangle may be moved in uniform steps along the edge of the straight edge. Section lines drawn along the edge of the triangle at successive steps will be correspondingly uniformly spaced.

Since the slide, including the turnbuckle, is of no greater thickness than the triangle, the device may be operated with either side of the triangle up, and with the movement of the triangle progressing either toward the right or the left. The angle at which the section lines are drawn may of course be varied by suitable positioning of the straight edge along which the triangle is operated. Lines such as the line 16 defining an angle of 30° to the hypotenuse of the triangle, may be at various angles, for obtaining a desired angularity of lines drawn along the hypotenuse. By alining the line 16 with a selected base line, and moving the straight edge against the triangle when so positioned, a desired angularity of the hypotenuse may be maintained as the triangle is moved along the straight edge.

I claim:

1. A drafting instrument comprising a triangle, a slide mounted for reciprocating movement parallel to an edge of triangle, and means substantially contained within the thickness of the triangle for adjusting the length of the slide to vary the distance the slide may be moved relative to the triangle.

2. A drafting instrument comprising a triangle, a slide mounted for reciprocating movement parallel to an edge of triangle, and a turnbuckle substantially contained within the thickness of the triangle for adjusting the length of the slide

to vary the distance the slide may be moved relative to the triangle.

3. A drafting instrument comprising a triangle having a guide slot parallel to one of its edges, a slide mounted within the slot for reciprocating movement therein, the thickness of the slide being substantially the same as the thickness of the triangle and the triangle and slide being relatively movable while resting flat against a supporting surface upon either of its faces, and means substantially contained within the thickness of the triangle for regulating the range of movement of the slide relative to the triangle.

4. A drafting instrument comprising a triangle having a guide slot inwardly spaced from one of its edges and having a widened section intermediate its ends, a slide mounted for reciprocating movement within the slot and comprising a pair of end pieces movable into sliding engagement with end portions of the slot through the widened center portion, and adjustable means substantially contained within the thickness of the triangle and connecting the end pieces in a desired spaced relation.

5. A drafting instrument comprising a triangle having a guide slot inwardly spaced from one of its edges and having a widened section intermediate its ends, a slide mounted for reciprocating movement within the slot and comprising a pair of end pieces separately movable into sliding engagement with end portions of the slot through the widened center portion, and a turnbuckle connecting the end pieces in a desired spaced relation within the slot, the thickness of the slide being substantially the same as that of the triangle whereby the triangle and slide may lie with either face flat against a supporting surface.
